(57) **CLAIM**

The ornamental design for a baby carrier, as shown and described.

DESCRIPTION

FIG. 1 is a front perspective environmental view of a baby carrier showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an unfurled view of the exterior of the baby carrier of FIG. 1.

The broken lines in the drawings showing a torso depict environmental subject matter that form no part of the claimed design. The remaining broken lines depict the portions of the baby carrier that form no part of the claimed design.

1 Claim, 9 Drawing Sheets
